UNITED STATES PATENT OFFICE.

SAMUEL F. HIMES, OF INDIANAPOLIS, INDIANA.

BASEBALL GAME.

1,417,063.

Specification of Letters Patent. Patented May 23, 1922.

Application filed November 24, 1919. Serial No. 340,183.

To all whom it may concern:

Be it known that I, SAMUEL F. HIMES, a citizen of the United States, and a resident of Indianapolis, county of Marion, and State 5 of Indiana, have invented a certain new and useful Baseball Game; and I do hereby declare that the following is a full, clear, and exact description thereof, reference being had to the accompanying drawings, in which 10 like numerals refer to like parts.

The object of this invention is to provide in a baseball game means operable by two or more persons and utilizing the pitching and batting skill of each, whereby the game 15 of baseball is simulated in a novel and improved manner.

One feature of the game is the replacement of most of the players by compartments grouped about the playing field.

20 The full nature of this invention will be understood from the accompanying drawings and the following description and claims.

In the drawings, which are made a part of 25 this application, Fig. 1 is a plan view of the invention showing a novel bat, a playing field and compartments grouped there-around. Fig. 2 is an enlarged side elevational view of the novel bat. Fig. 3 is an 30 enlarged plan view of a ball receiving compartment and shows the means for deflecting and retaining the balls batted within the same.

In the drawings 10 indicates a baseboard 35 suitably marked to represent a miniature baseball diamond, the bases, foul lines, pitcher's box and batter's box. The base-board is provided with side walls 11 of suitable height. Grouped around one end and 40 both adjacent sides of the baseboard there are provided a plurality of compartments 12, as shown, each compartment having a suitable opening or entrance 13 facing towards the batter's box through which a batted ball 45 may pass. As shown in Fig. 3 certain of the compartments are provided with a pin 8 positioned within the compartment and back of the opening to deflect and retain a ball entering the same. These compartments 50 may be varied suitably and may carry designating numerals thereon, each compartment either having a numerical value, but preferably representing one of the known plays performed in the actual game of baseball.

The novel bat is herein shown comprising 55 a handle portion 14, the same being spaced from the baseboard to permit a pitched ball to pass beneath and having a depending resilient striking portion 15, preferably of rubber, near the striking end of the bat. 60 The bat is pivotally mounted near the handle portion upon a pin 16 suitably secured to the baseboard 10 and normally rests in the position shown in Fig. 1. One end of a retaining spring 17 is secured suitably to one 65 end of an arm 18 fixed upon the lower end of the pin 16, while the other end is secured by a hook bolt 19^a adjustably mounted in the baseboard by a wing nut 19^b. The bat is also provided with a finger pin 20 having a 70 ball head for ease in grasping.

In the game one of the players operates the bat by pulling it back and releasing it when the ball is delivered over the plate, the ball being delivered by the other player. 75 He pitches the same from a position directly in line with the pitcher's box and second base and from a point near the opposite edge of the baseboard. The pitcher rolls the ball from the before mentioned position and 80 should endeavor to deliver the same either over or near the edge of the homeplate so as to tempt the batter to strike at it. The ball may be of any suitable material, such as of steel or marble or it may be of resilient 85 material.

When the ball is hit by the bat, the same is projected to some portion of the playing field or off of the board. Balls batted off the board are considered as putouts. The 90 position that the ball assumes determines the value of the play.

Herein are shown twenty-three compartments numbered in order from twenty-one to thirty-two and which have the following 95 values:

Compartment No. 21.

The ball is considered a foul fly and the 100 batter is out. If the ball enters the left compartment, the third baseman is credited with the putout. Similarly if the ball enters the right compartment, the first baseman is credited with the putout.

Compartment No. 22.

Bunted ball and batter is out. If in the left compartment, credit the third baseman

with the putout. If in the right compartment, credit the first baseman with the putout.

Compartment No. 23.

- 5 If two or more men are on base, the play is considered a double steal. If there are no men on base, the batted ball is counted as a single into the right or left field respectively 10 as the ball enters the right or left compartment.

Compartment No. 24.

- 15 If a man is on base, the man is out stealing. If two or more men are on bases, the man farthest advanced is out stealing. If no men are on base, the ball counts as a strike against the batter. Credit the putout 20 to the appropriate player.

20 *Compartment No. 25.*

The batter is safe at first base on an error and all men on base advance one base.

Compartment No. 26.

- 25 The ball is considered a sacrifice hit and the putout may be credited to the right or left fielder as the ball enters the right or left compartment respectively. All men on base advance one base. If no men are on base, the ball counts as a strike against the batter. No runner can advance on the third out.

Compartment No. 27.

- 35 The ball is considered a three base hit to right or left field respectively as the ball enters the right or left compartment. All men on bases score.

40 *Compartment No. 28.*

The ball entering the right or left compartment is considered a single to right or left field respectively. If a man is on second base and the ball enters the left compartment, the base runner scores.

Compartment No. 29.

- 45 If any men are on base, the runners steal the next base, but if no men are on base, the batter is credited with a ball. If two men are on base, the leading base runner steals and advances one base.

Compartment No. 30.

- 55 The ball entering the right or left compartment is considered a two base hit to right or left field.

Compartment No. 31.

- 60 If a man is on base, the man and batter are both out, the ball being considered a double play. If the player is on third or second base, credit the third baseman or shortstop respectively with the putout and 65 left fielder with a putout, as well as, an as-

sist if the ball enters the left compartment. If the ball enters the right compartment, credit the second baseman or first baseman respectively with a putout and the right fielder with a putout and an assist.

Compartment No. 32.

The ball entering this central compartment is considered a homerun, and all men on bases score.

75 The pitcher must deliver or roll the ball near the edge or over the homeplate so as to tempt the batter to strike at it. Balls and strikes are called as in a regular game. Balls hit by the batter and not going into 80 the compartment are counted as fly balls which have been caught and are counted as putouts. Should the pitcher roll the ball against the pivotal base of the bat, the batter is considered to have been hit by a pitched 85 ball, which entitles the batter to advance to first base and all other players on base to advance a base when forced to do so, as in the regular game. Balls which strike the compartments and return back of the foul 90 lines are played as strikes, thus penalizing the batter for batting the ball too hard, three strikes as in the regular game constitute an out and the pitcher is credited with a strikeout. Three putouts as in the regular 95 game retire the side then batting.

Should the batter hit the ball light enough so that the same stops within the infield, the play is considered a safe bunt, all players on base advancing a base. The batter is 100 considered safe at first base. This play, however, is not permitted if two men are already out, the play being considered an out.

105 The rules further provide that if a man 9 is on second base, the runner may be advanced slightly so as not to interfere with the pitcher delivering the ball to the batter. Should the ball stop in the entrance to any 110 compartment, the ball is played as if the same had entered the compartment if one-half of the ball is within the outer edge 113 of the entrance to the compartment.

115 There is further provided in each of the adjacent corners near the homeplate a compartment 33, the same being adapted to receive suitable miniature men or other player designating objects, as well as additional balls. These compartments may represent the respective player's benches.

120 From the foregoing it will be understood that the invention provides for a unique and novel miniature baseball game wherein pitching and batting skill is required, and wherein the various baseball plays may be 125 made crediting alike the results of both the team in the field and the team at bat.

130 It is to be understood that the structure shown herein and the rules cited may be modified suitably without departing from

the invention, and the same is not to be limited by the foregoing detailed description.

The invention claimed is:

- 5 1. A baseball game including a flat base-board suitably marked to represent a miniature diamond, the bases being positioned intermediate the corners of the board, compartments arranged around the end opposite the second base and along the adjacent sides thereof up to the first and third bases, said compartments projecting above the plane of the board and being positioned around the edges of said board to provide a relatively 10 large and unobstructed outfield area, each compartment having an opening therein adapted to receive the batted ball, a bat positioned adjacent the home plate for batting the ball into one of said compartments, and a compartment at each of the other corners opposite the compartments for receiving surplus miniature players and balls, said players being positionable upon the bases and 15 playing fields as desired.
- 15 2. A baseball game including a flat base-board suitably marked to represent a miniature diamond, the bases being positioned intermediate the corners of the board and the infield being cleared of all obstructions, compartments arranged around the end opposite the second base and along the adjacent sides thereof up to the first and third bases, said compartments projecting above the plane of 20 an upstanding pin positioned within each compartment adjacent the opening thereof for deflecting the batted ball into said compartment and for retaining said deflected ball in said compartment after the same has 25 passed through the opening thereof.
- 25 3. A baseball game including a flat base-board suitably marked to represent a miniature diamond, the bases being positioned intermediate the corners of the board and the 30 infield being cleared of all obstructions, compartments arranged around the end opposite the second base and along the adjacent sides thereof up to the first and third bases, said compartments projecting above the plane of

the board and being positioned around the 35 edges of said board to provide a relatively large and unobstructed outfield area, each compartment having an opening therein adapted to receive the batted ball, a bat positioned adjacent the home plate for batting 40 the ball into one of said compartments, and a compartment at each of the other corners opposite the compartments for receiving surplus miniature players and balls, said players being positionable upon the bases and 45 playing fields as desired.

3. In a miniature baseball game, the combination of a board suitably marked to represent a miniature diamond, means associated therewith to receive a batted ball, and a bat 50 for batting said ball, said bat being pivotally supported upon said board for swinging movement in a plane parallel to the board and comprising a handle portion spaced from the board and extending from 55 said pivotal support, a depending resilient striking portion adjacent the end of said bat and extending towards said board, said striking portion and said bat providing a space between the pivotal support and the 60 normal striking position, an angular extension upon said bat providing a finger piece for swinging the bat in striking relation, and means for returning said bat to the striking position. 65

In witness whereof, I have hereunto affixed my signature.

SAMUEL F. HIMES.
